COMBINATION LOCK OPENER

Isaac Jacobs, 97 Falmouth Ave., East Paterson, N.J.

Filed Apr. 21, 1958, Ser. No. 729,663

9 Claims. (Cl. 70—442)

My invention relates generally to devices and methods for opening combination locks without specific knowledge of the combination and more particularly relates to a device and a method for imparting vibration to the members constituting the combination lock so that they may automatically adjust themselves to unlocked position.

It is among the objects of my invention to provide a method for opening a combination lock without specific knowledge of the combination.

Another object of my invention is to provide a device and method for imparting physical impulses to the members of a combination lock to cause them to move haphazardly until such time as they reach an unlocked position.

Yet another object of my invention is to provide a device and a method for rapidly setting a combination lock in an unlocked position without knowledge of the combination.

Yet a further object of my invention is to provide a device and method to enable the unskilled to set a locked combination lock in an unlocked position without knowledge of the true combination.

A further object of my invention is to provide a device and method for opening a combination lock without knowledge of the combination in such a manner that no physical damage is caused to the lock mechanism or the safe or similar article to which the lock is applied.

Among the further objects of my invention is to provide a device and method for setting a combination lock in an unlocked position which method shall be easy to practice, rapid, and shall not require any particular skill; and the device shall be relatively inexpensive, durable, easy to maintain and operate.

These objects and advantages as well as other objects may be achieved by the device and method shown by way of illustration in the drawings in which:

Figure 1 is a front elevational view of a safe to which the device for opening combination locks has been applied;

Figure 2 is a side elevational view of the device for opening combination locks;

Figures 3, 4, 5 and 6 are diagrams detailing the movement of the components of the device during the course of its operation; and

Figure 7 is a view of the clamp for the combination knob.

When a combination for a combination lock is lost or unknown, the attack upon the problem of opening a safe or similar item may involve the use of a skilled operative who, through his sense of touch, or through acuity of hearing, is able to determine the movement of the mechanism and arrive at the proper opening position through manipulation of the knob and the exercise of the aforementioned modalities. There are however numerous combination locks which are specifically designed, with varying degrees of success, to defy such methods of manipulation. In some cases, auxiliary listening devices in the nature of microphone and electronic ampli-

2

fiers relay the information to the operator who is seeking to unlock the combination lock. When the skill of the operator fails, and the auxiliary devices do not aid in the accomplishment of the desired results, there is usually only one remaining expedient and that is to resort to explosive forces in order to open the combination lock.

The present invention is intended to avoid the necessity for the use of a highly skilled operative in order to open a combination lock without the combination or to avoid the necessity for destroying the lock by the application of forces. Broadly, a combination lock frequently involves the use of a combination knob mounted on a rotatable shaft. The shaft has a plurality of wheels rotatably mounted thereon. One of these wheels may be actually keyed to the shaft. Each of these wheels is provided with a slot and the wheels have means mounted thereon that will cause the rotation of an adjacent wheel, under some circumstances to move its neighboring wheel. When the combination knob has been manipulated in accordance with the proper numeric sequence dictated by the combination, the wheels are all adjusted to a position in which their separate slots are brought into alignment and a "fence" will drop into the slots thereby unlocking the combination lock and permitting the lock-bolt to be withdrawn. It should be noted that the failure of any slot to be brought into alignment with the remaining slots is sufficient to prevent the fence from falling into the slots and setting the lock to unlocked position.

The present method and device is in essence a clamp 30 that is secured to the combination knob. Movement is imparted to this clamp by a connecting rod mounted on a crank shaft driven by an electric motor. The clamp will cause the reciprocal movement of the combination knob and the consequent reciprocal movement of the shaft. This movement will merely involve a few degrees of turning of the shaft, rapidly back and forth. Such movement will impart a vibration or an oscillation to the shaft and cause the wheels that are rotatably mounted thereon to embark upon random or haphazard rotation. 40 The first wheel is usually easy to set manually through the exercise of the sense of touch, so that its slot is in alignment with the fence. The remaining wheels, will continue, each separately, its random movement until the respective slots are disposed in coincidence with the manually set slot of the first wheel. It has been found that such random movement of the freely rotatable wheels of the combination lock, which wheels are not keyed to the shaft, will cease when the slots in the wheels are in position to receive, the fence. When all of the wheels are disposed, by reason of the vibratory movement of the shaft or by reason of its oscillation, in position to receive the fence, the fence drops into the slot and the combination is unlocked. This usually takes no more than a few minutes.

55 Referring now to the drawings in detail, my device for opening combination locks has a clamp 11. The form of this clamp is not critical. It can be any form of clamp which will grip the combination knob 12 of a safe 13 and hold it firmly during oscillatory or reciprocal movement without allowing it to slip.

I have illustrated one suitable species of clamp which consists of a pair of unitary jaws 14, 14 which are resilient and may be drawn together by the nut 10 and bolt 15 passing through the jaws 14, 14. The jaws have gripping surfaces 16, 16 shaped to engage and hold a combination knob 12.

70 The opposite end 17 of the jaws 14, 14 is provided with a vertical passage to receive a flexible connecting rod or link 18. A set-screw 19 will hold the jaws 14, 14 to the rod. The link 18 is attached to a crank 20. The crank 20 is rotatably mounted on a crank-housing 21.

The link 18 extends into the housing 21 through a slot 22.

One end 23 of the crank 20 extends outside of the housing 21 and is provided with a flexible tubular coupling 24. A shaft 25 is attached to and extends from the coupling 24. This shaft 25 may be connected to a conventional electric drill as a driving means or the crank 20 may be the motor shaft of an electric motor 26.

The operation of the motor 26 causes the crank 20 to reciprocate the link 18. The link being of resilient stock, will whip or flex, as shown in Figures 3, 4, 5 and 6 to cause the clamp 11 to oscillate the knob 12 back and forth through a minute arc of perhaps 3.25 to 7.50 degrees. Since the knob 12 has already been set manually by sense of touch, with a slot on a keyed wheel in alignment with the fence, the rapid oscillation of the knob 12 will cause the wheel which is keyed to the knob to move in and out of alignment with the fence. The same oscillation of the shaft connected to the knob will cause the wheels which are not keyed to the combination knob shaft to move at random until their slots coincide with the fence. The contact of the unkeyed wheels with the shaft is not entirely friction-free; each reciprocal movement of the shaft will overcome the inertia of the unkeyed wheels and cause some random movements of the wheels. It has been found that the slots, once aligned with the fence, will not be vibrated or reciprocated to move beyond this friction free-point where there is no contact with the fence. When all the slots, through random movement (except the slot in the wheel which is keyed to the shaft and has been pre-set) are in alignment, the fence drops into the slots and the combination lock is open.

Attention is directed to the fact that in a combination lock, there are engaging means on each of the wheels which contact the adjacent wheel at certain positions. It is therefore desirable, as well as standard operating procedure for all locksmiths who attempt to open combination locks without the combination, to set each of the wheel elements at a position wherein the successive 35 wheels shall be positioned in non-engaged relation with each other. This standard operating procedure is recommended for my apparatus and method in order that the random motion of the wheels will proceed rapidly without any interference by reason of engagement of one wheel with an adjacent wheel. Thus in order to set a combination lock for the start of an opening operation, a four-dial lock would have its combination turned four complete full turns in one direction, succeeded by alternately 3, 2 and 1 turns in opposite directions. This sets up the unkeyed wheels for free unhampered random motion.

It will be seen that I have shown a device for imparting rapid oscillatory movement to a combination knob by oscillating a clamp attached to the knob. The form of the clamp, or the link, and of the crank may be changed. They each may have known equivalents in form as well as function which may be substituted. All of these substitutions and changes are contemplated as being within the scope of the appended apparatus claims.

Likewise, as to the method, the steps thereof may be varied as to the manner of their performance, and such variation or changes as are equivalent in function are contemplated as being within the scope of the appended method claims.

I claim:

1. A combination lock opener comprising a crank, a means to support the crank for rotation, a means connected to the crank for rotatably driving the crank, a flexible connecting rod pivotally attached at one end to the crank for rapid reciprocation of the connecting rod, a gripping means attached to the other end of the connecting rod, the gripping means engageable with the combination knob of a combination lock.

2. A combination lock opener comprising a rotatable

crank, a driving means for the crank, a flexible connecting rod pivotally attached at one end to the crank for rapid reciprocation of the connecting rod, a clamp attached the other end of the flexible connecting rod, the clamp engageable with the combination knob of a combination lock.

3. A combination lock opener in which a combination knob is attached to a rotatable shaft, rotatable unkeyed slotted wheels are on the shaft, and there is a fence adapted to enter the slots; comprising a clamp to grip the combination knob of a combination lock, a means connected to the clamp for rapidly reciprocating the clamp in engagement with the combination knob, to impart a rapid reciprocating movement to the knob and to the shaft connected to it and random movement of the lock's unkeyed wheels on the shaft until the wheels' slots are all in registration with the fence in the lock.

4. A method for opening a combination lock comprising manually setting the keyed wheel of a combination lock to open position by tactile sense, mechanically reciprocating the combination knob to impart random movement to the unkeyed wheels in the combination lock, continuing such mechanical reciprocation until each of the wheels has moved to open position and the fence falls into the coincident open slots.

5. A method for opening a combination lock comprising manually setting the lock at normal starting position with the wheels disengaged from each other, manually setting the keyed wheel of the combination lock to open position by the tactile sense, reciprocating the combination knob in opposite directions, imparting a random movement to the unkeyed wheels of the combination lock until the fence falls into the coincident open slots.

6. A method for opening a combination lock comprising manually setting the lock at normal starting position with the wheels disengaged from each other, manually setting by tactile sense the keyed wheel of the combination lock to open position with its slot positioned to receive the fence, mechanically reciprocating the combination knob, imparting random movements to the unkeyed wheels of the combination lock until the slots of all of the wheels are simultaneously in registration with the fence and their random movement is stopped by the fence dropping into the slots.

7. A method for opening a combination lock comprising manually setting the lock at normal starting position with the wheels disengaged from each other, manually setting by tactile sense the keyed wheel of the combination lock to open position with its slot positioned to receive the fence, mechanically reciprocating the combination knob a few degrees in opposite directions imparting random movements to unkeyed wheels of the combination lock until their random movements stop with the fence dropping into the coincident slots.

8. A combination lock opener for a combination lock in which a combination knob is attached to a rotatable shaft, rotatable unkeyed slotted wheels are on the shaft, and there is a fence adapted to enter the slots comprising a clamp engageable with the combination knob, means for rapidly reciprocating the clamp to impart movement to the shaft whereby random movement is imparted to the wheels.

9. A combination lock opener for a combination lock in which a combination knob is attached to a rotatable shaft, rotatable unkeyed slotted wheels are on the shaft, and there is a fence adapted to enter the slots comprising a means for gripping the combination knob of a lock, means for rapidly reciprocating the gripping means to impart movement to the shaft whereby random movement is imparted to the wheels.
